J. M. MELLIS AND C. A. SPLAYFORD.
DIRECTION INDICATOR FOR ROAD VEHICLES.
APPLICATION FILED NOV. 27, 1917.

1,321,933.

Patented Nov. 18, 1919.

UNITED STATES PATENT OFFICE.

JAMES M. MELLIS AND CHARLES A. SPLAYFORD, OF VANCOUVER, BRITISH COLUMBIA,
CANADA.

DIRECTION-INDICATOR FOR ROAD-VEHICLES.

1,321,933.

Specification of Letters Patent. Patented Nov. 18, 1919.

Application filed November 27, 1917. Serial No. 204,224.

To all whom it may concern:

Be it known that we, JAMES M. MELLIS and CHARLES A. SPLAYFORD, citizens of the Dominion of Canada, residing at Vancouver, in the Province of British Columbia, Canada, have invented certain new and useful Improvements in Direction-Indicators for Road-Vehicles, of which the following is a specification.

- 10 This invention relates to a direction indicator for use on self-propelled road vehicles to indicate to the pointsman at a crossing or to adjacent vehicles a desire or intention to turn. The device comprises
15 a semaphore pivotally mounted on one or both sides, preferably of the wind-shield, to turn on a vertical axis from a normal position indicating the forward direction to right or left as the case may require.
20 As city traffic regulations generally call for the driver of a vehicle to indicate the direction of a desired or intended turn by the hand, this semaphore is shaped to represent a hand, and to render the same visible
25 at night the semaphore itself carries a lamp, the light from which is reflected on both surfaces of the hand which are white enameled or otherwise reflecting. While the light is reflected on both faces of the hand,
30 it is shielded from direct view from either face but the shield has a red lens on each side, so that when the semaphore is turned prior to turning the vehicle at a crossing the white hand shows conspicuously and the
35 red light indicating danger is shown adjacent. This semaphore is manipulated by the hand of the driver and simultaneously with movement of it to either side electrical connection is made in an alarm bell circuit to
40 ring a bell or gong and such will continue to ring until the turn having been effected the semaphore arm is returned to its straight ahead position and the bell circuit opened.

The invention is particularly described in
45 the following specification, reference being made to the drawings by which it is accompanied, in which:

Figure 1 is a side elevation showing the attachment of the semaphore indicator to
50 the frame of the wind-shield and the operating mechanism to the steering wheel standard of a car.

Fig. 2 is a sectional plan of the same.

Fig. 3, a sectional plan of the flexible line
55 connection of the operative mechanism to the semaphore spindle.

Fig. 4 is an end view of the semaphore hand.

The indicating semaphore is preferably contoured to represent a hand and the fingers 2 may be embossed to impart a measure of rigidity to it, thus enabling it to be made of very light thin metal. That portion of it adjacent the wrist is made in two pieces which are bent outward from one another to form a shield 3 for the lamp 5 which is inserted between them, and one of these sides is hinged as at 4 to afford access to the lamp, etc.

In the end of this shield portion 3, which is immediately adjacent the fingers 2, a lens or reflecting prisms 6 are secured to reflect the light of the lamp 5 upon each face of the hand portion 2, which faces are enameled white to show up distinctly under the light so directed on them. Red glasses 7 are inserted in each side of the lamp shield 3 that will draw attention forward and aft of the machine to the danger of approach while the semaphore is turned to the right or left.

This semaphore 2-3 is secured on a stem 8 which is mounted to turn on a vertical axis in bearings formed in a bracket 9 removably clamped in any convenient manner 85 to the frame 10 of the wind-shield. The lower end of the stem 8 is produced below the bearing bracket 9 and on it is secured a grooved sheave or segment 11 to the arc of which is secured at 12 a flexible line 13. 90

Both ends of this flexible line 13 are led through a small tubular duct 14 and are connected to a similar sheave or segment secured on a handle lever 15 which is mounted on a pivot 16 in a bracket 17 secured on the 95 steering wheel standard 19 or other part of the vehicle convenient to the hand of the driver.

By this handle lever 15 the semaphore 2-3 is retained in the normal position, that 100 is, in the direction of movement of the vehicle, or may be turned through an arc of ninety degrees to either side. The bracket 17 may have notches 18 to arrest and retain the handle lever in the required positions, 105 or it may be preferable to have these retaining notches on the bracket of the semaphore arm itself.

That an audible signal may be given of the vehicle's wish or intention to turn, an 110 electric bell circuit 20 21, shown diagrammatically in Figs. 1 and 2, is connected at

22 to the semaphore 3—2 which is insulated from the bracket in which it is mounted and at 23 to an adjacent contact on the bracket or housing of the mechanism, which contact 5 connection 23 is in the path of a resilient contact 24 on the semaphore arm, so that when the arm is in the normal or forwardly directed position the bell circuit is open, but when moved to ninety degrees from 10 that position to indicate an intended change of direction, the bell circuit is closed and the bell will continue to ring until the semaphore is returned to its normal position after the turning has been effected. 15 This alarm not only serves to intimate to the pointsman or to any adjacent vehicle or pedestrian that the vehicle intends to turn but instres that the signal will be returned to its normal position after the turn 20 has been effected.

We do not desire to be confined to the exact construction of the semaphore arm here set forth or to the exact means illustrated for mounting and operating the 25 same, although we consider that the manner

here shown is both simple, effective and inexpensive. We believe that the essence of the invention chiefly resides in the particular manner of delivering the light on both faces of the semaphore arm.

30

Having now particularly described our invention, we hereby declare that what we claim as new and desire to be protected in by Letters Patent, is:

A direction indicator comprising a lamp, 35 a shield pivotally mounted to turn on a vertical axis and inclosing the lamp on all sides except that opposite the pivot, a portion projecting in a vertical plane from the mid-width of the open end of the shield, a refracting prism located within the shield at each side of such projecting portion and in the front of the lamp for focusing the rays of the lamp directly on the sides of said projecting portion, and means for turning 40 45 the shield on its pivot.

In testimony whereof we affix our signatures.

JAMES M. MELLIS.

CHARLES A. SPLAYFORD.
